UNITED STATES PATENT OFFICE.

CHARLES F. KELLOM, OF DELAIR, NEW JERSEY.

GREASE-CUP OR LUBRICATOR.

SPECIFICATION forming part of Letters Patent No. 645,227, dated March 13, 1900.

Application filed May 13, 1899. Serial No. 716,626. (No model.)

To all whom it may concern:

Be it known that I, CHARLES F. KELLOM, a citizen of the United States, residing at Delair, in the county of Camden, State of New Jersey, have invented a new and useful Improvement in Grease-Cups or Lubricators, which improvement is fully set forth in the following specification and accompanying drawings.

10 My invention consists of a grease-cup or lubricator in which provision is made in a simple and effective manner for agitating or breaking up the lubricant to prevent coagulation or hardening thereof, which sometimes occurs, and also for raising the temperature thereof sufficiently to insure a satisfactory feed thereof.

It further consists of novel details of construction, all as will be hereinafter fully set forth, and particularly pointed out in the claims.

The lubricator can be applied to shaft hangers and bearings of various kinds, and for the purpose of illustration I have shown a well-known form of shaft-hanger and will now particularly describe the same.

Figure 1 represents a perspective view of a lubricating device embodying my invention and a portion of a shaft and hanger to which the same is applicable. Fig. 2 represents, on an enlarged scale, a section on line xx , Fig. 1.

Similar letters of reference indicate corresponding parts in the figures.

Referring to the drawings, A designates the lubricating device, the same consisting of a cup B, having its lower portion C screw-threaded to engage the threaded seat or socket D, the latter being provided with a base E and depending walls F, that rest upon the bearing G, in which latter is the shaft H. The bearing has an opening J, in which the lower portion K of the cup B is seated, said portion K having the opening L therein, which communicates with the passage M, leading to the shaft H.

N designates a rotatable cap mounted upon the upper portion of the cup B, said cap having an opening P at or near the center thereof and another opening Q near its outer edge.

50 R designates the agitator, which consists of a stem U and finger T, joined by a top member S. The stem U is helical or spiral in shape

and preferably composed of copper or similar material and extends to and rests upon the rotatable shaft H, while the finger T enters 55 the opening Q and is located in proximity to the inner side of the cup B and in the present instance consists of a flat thin strip of material, as will be evident from Fig. 2.

The device is held in position upon the cylinder or bearing by any suitable means, in the present instance by the strip or wire V, whose ends engage the walls F.

The operation is as follows: The parts normally appear when assembled as indicated 65 in Figs. 1 and 2, the cup B being supplied with the lubricant. If for any reason the lubricant becomes hardened or coagulated, which sometimes occurs at different points near the cup B, it is only necessary for the attendant 70 to turn or rotate the cap N, whereby it will be seen that the finger T sweeps around the inner face of the cup B, and thus scraping the lubricant from said face, so that it passes to the center of the cup, where it is again acted 75 on by the stem, said stem when turned also serving as an auger to screw or force down the lubricant, thus more effectively feeding it to the place of service, said stem also producing a passage whereby the lubricant can readily 80 flow through the cup, assisted by the heating of said stem, due to its frictional contact with the shaft.

The base E, with the walls F, adapts the lubricator to be nicely seated on the bearing G. 85

The bottom of the cup is conical, so that it will nicely fit the opening in the bearing and adapt itself to openings of different diameters or depths.

Having thus described my invention, what 90 I claim as new, and desire to secure by Letters Patent, is—

1. In a lubricator, a cup having a freely-rotatable cap, and a finger situated within said cup and near one side thereof, said cap and finger being suitably connected, whereby the latter can be rotated by the former.

2. In a lubricator, a cup having a freely-rotatable cap, and an agitator situated within said cup, said cap and agitator being suitably connected, whereby the latter can be rotated by the former.

3. In a lubricator, a cup having a freely-rotatable cap, and a stem and a finger situated

within said cup, said finger being situated near one side of the cup and suitably connected with said cap to be rotated thereby.

4. In a lubricator, a cup having a rotatable cap provided with a finger extending into said cup from one side thereof and situated adjacent to and practically parallel with the inner face of the side wall thereof.
5. In a lubricator, a cup provided with a rotatable cap, having central and side openings, a stem passing freely through said central opening and resting at its lower end upon the rotatable part to be lubricated, and a finger connected with said stem and passing freely through said side opening.
15. In a lubricating device, a cup threaded

at its lower portion and provided with a base portion having an opening therethrough, a socket provided with projecting walls and fastening devices for the reception of said cup, a rotatable cap mounted on said cup and having openings therein, and an agitator mounted in said openings and adapted to be moved in unison with said cap, said agitator having depending limbs within said cup of different lengths, the inner limb being helical or spiral and the other or outer limb being located in proximity to the interior of said casing.

CHARLES F. KELLOM.
